CLAIM

The ornamental design for a portable beverage cooler with integral supporting means, as shown and described.

DESCRIPTION

FIG. 1 is an exploded perspective view of a portable beverage cooler with integral supporting means showing my new design, the broken lines represent wheels which are part of the environment and are not claimed.

FIG. 2 is a top perspective view of the cooler body.

FIG. 3 is a top, rear perspective view of FIG. 2.

FIG. 4 is a top, front perspective view of FIG. 2.

FIG. 5 is a front view of FIG. 2.

FIG. 6 is a rear view of FIG. 2.

FIG. 7 is a left side view of FIG. 2, the right side being a mirror image.

FIG. 8 is a top plan view of FIG. 2.

FIG. 9 is a bottom plan view of FIG. 2.

FIG. 10 is a top perspective view of the beverage tray.

FIG. 11 is a front view of FIG. 10, the rear view being a mirror image.

FIG. 12 is a left side view of FIG. 10, the right side view being a mirror image.

FIG. 13 is a top plan view of FIG. 10.

FIG. 14 is a bottom plan view of FIG. 10.

FIG. 15 is a top perspective view of the food tray.

FIG. 16 is a front view of FIG. 15, the rear view being a mirror image.

FIG. 17 is a left side view of FIG. 15, the right side view being a mirror image.

FIG. 18 is a top plan view of FIG. 15.

FIG. 19 is a bottom plan view of FIG. 15.

FIG. 20 is a top perspective view of the lid.

FIG. 21 is a front view of FIG. 20, the rear view being a mirror image.

FIG. 22 is a left side view of FIG. 20, the right side view being a mirror image.

FIG. 23 is a top plan view of FIG. 20; and,

FIG. 24 is a bottom plan view of FIG. 20.

The parts of the cooler are shown separately for ease and clarity of illustration.
